UNITED STATES PATENT OFFICE.

CLARENCE M. BEADENKOPF, OF WILMINGTON, DELAWARE.

TRAFFIC-SIGNAL.

1,821,702.

Specification of Letters Patent. Patented Nov. 11, 1919.

Application filed July 17, 1918. Serial No. 245,370.

To all whom it may concern:

Be it known that I, CLARENCE M. BEADENKOPF, a citizen of the United States, residing at Wilmington, in the county of New Castle and State of Delaware, have invented certain new and useful Improvements in Traffic-Signals, of which the following is a specification.

This invention relates to an improved traffic signal for motor vehicles and has as its primary object to provide a device of this character whereby a driver may readily indicate his intended course of action so as to thereby eliminate any confusion of other traffic drivers as well as of pedestrians.

The invention has as a further object to provide a device of this character which may be attached to the wind shield of a vehicle, or in the instance of a closed vehicle, may be attached to one side of the body thereof, and manually operated from the driver's seat.

The invention has as a still further object to provide a signal employing a plurality of semaphore arms or blades which may be selectively moved to active signaling position and wherein the said blades may, at night, be illuminated so that the signals carried by the respective blades may be readily observed.

A still further object of the invention is to provide a device wherein the signal lamp employed may also be used as a pilot danger signal light.

And the invention has as a still further object to provide a signal of the above described character which will be particularly simple in construction and which may be installed with a minimum of difficulty.

Other and incidental objects will appear as the description proceeds. In the drawings wherein I have illustrated the preferred embodiment of the invention, and wherein similar reference characters designate corresponding parts throughout the several views:

Figure 1 is a fragmentary rear elevation showing my improved signal applied to the wind shield of a conventional type of motor vehicle.

Fig. 2 is a sectional view taken on the line 2-2 of Fig. 1 and more particularly illustrating the normal disposition of the levers employed for selectively elevating the semaphore blades of the signals to active signaling position.

Fig. 3 is a transverse sectional view more particularly illustrating the mounting of the levers and showing one of the semaphore blades removed, and

60

Fig. 4 is a vertical sectional view showing the manner in which the actuating levers of the semaphore blades are adapted to be locked in depressed position for holding the semaphore blades elevated.

65

In carrying out the invention I employ a lamp casing 10 in which may be arranged a suitable electric lamp 11 and closing the ends of the casing are front and rear glass panes 12 and 13 respectively. The front pane may be of red or white glass while the rear pane is preferably of red glass. Projecting laterally from one side of the casing is a supporting arm 14 adapted for attachment to an upright of a motor vehicle wind shield. In the drawings, I have, for convenience, conventionally shown a wind shield in connection with a conventional type of motor vehicle body 15 and, as particularly brought out in Fig. 2, the lamp casing 10 is mounted at the left hand side of the wind shield. In this connection it may be stated that while I have illustrated my improved signal as attached to a vehicle wind shield, still, as will appear as the description proceeds, the device may, in any instance where the vehicle is provided with a closed body, be attached directly to the body to be operated from the driver's seat therein. Formed in the outer side of the lamp casing is an opening 16 and mounted within the said casing at the inner side of the lamp 11 and opposite said opening, is a reflector 17 adapted to project the rays of light from the lamp through the opening.

90

Connected in any approved manner to the bottom side of the lamp casing 10 to depend vertically therefrom is an oblong signal casing 18. This casing is preferably formed of sheet metal and is provided with side walls 19, a bottom wall 20 and a back wall 21. As shown in Figs. 2 and 4, the signal casing is closed at its top by the lamp casing while the front of the signal casing is open. Mounted within the signal casing is a plurality of oblong semaphore blades 22. These blades may be formed of sheet metal, celluloid, or other approved material and at their upper ends are swingingly supported by a pivot rod 23 extending between the side walls 19 of the signal casing and through the upper ends of the said blades. The blades are disposed,

105

110

in substantially parallel relation and are of a size to be normally received in inactive position within the signal casing to be housed thereby. Five of the blades are preferably employed and these blades respectively bear upon opposite sides thereof the words stop, right, left, ahead and pass.

Extending transversely between the side walls 19 of the signal casing adjacent the back wall thereof and in a plane below the pivot rod 23 is a second pivot rod 24, and swingingly mounted upon this pivot rod is a plurality of levers 25 of the bell crank type. The inner arms of these levers are of uniform length and project loosely through the back wall 21 of the signal casing. Adjacent their inner ends, the said inner arms of the levers receive the pivot rod 24 there-through while, at their outer ends, these arms carry substantially U-shaped guide members 26 slidably embracing the bottom edges of the semaphore blades. The outer arms of the levers are graduated in length from the arm of the rearmost lever, which is the shortest, to the arm of the foremost lever, which is the longest. At their outer ends these arms carry knobs or buttons 27 and these knobs preferably bear respectively, the letters S, R, L, A and P, beginning with the shortest arm. These letters are, of course, designed to identify each of the levers with its particular semaphore blade. As clearly brought out in Figs. 2 and 4 of the drawings, the semaphore blades 25 will normally gravitate to assume their inactive position housed within the signal casing and the weight of these blades bearing against the inner arms of the levers will serve to normally hold the levers in position with the inner arms thereof extending downwardly within the casing behind the said blades and with the outer arms of the said levers projecting laterally from the casing into the vehicle body. Mounted upon the back wall 21 of the signal casing is a plurality of resilient catch members 28 projecting laterally from the casing and adapted to receive and hold the free ends of the outer arms of the levers 25 between the resilient sides thereof. Preferably, the catch members are formed from a single strip of suitable resilient material bent to define the said members and suitably secured to the signal casing.

As will now be clear in view of the preceding description, the outer arms of the levers 25, being held to normally project laterally from the signal casing at the inner side of the wind shield of the vehicle, may be readily reached from the driver's seat and, owing to the graduated length of the lever arms, any one particular arm may be readily grasped by the driver. For giving a signal, the arm so grasped is swung downwardly to rock that one of the levers

25 upon the pivot pin 24. Downward movement of the outer arm of such lever will, of course, swing the inner arm of the said lever upwardly when the guide member 26 at the free end of the inner arm will ride along the bottom edge of the corresponding semaphore blade for elevating the said blade to horizontal active position, as shown in Fig. 4, projecting laterally from the signal casing. For retaining the blade in active position, the outer arm of the lever may then be engaged within its catch member 28, as also shown in Fig. 4, when the semaphore blade will be rigidly held elevated. However, as will be seen, the outer arm of the lever may be readily disengaged for freeing the said lever when the semaphore blade will immediately gravitate to normal inactive position housed within the signal casing. I accordingly provide an arrangement 85 wherein the driver may, by selective actuation of the semaphore blades, readily indicate an intention to stop, an intention to turn to the right, an intention to turn to the left, an intention to proceed straight 90 ahead, or may give a signal to other traffic to pass. Any tendency of confusion of other traffic drivers or of pedestrians may accordingly, by the use of my improved device, be materially lessened. At night, the 95 lamp 11 may be energized from a storage battery or other suitable source of electrical energy upon the vehicle. The rays from this lamp will be projected by the reflector 17 through the openings 16 against the 100 semaphore blades when elevated to active position. The blades may thus be easily seen so that the signal will prove equally as effective for use at night as in the day time. Furthermore, the lamp 11 may be 105 employed as a pilot danger signal lamp for the vehicle when standing so as to permit, if desired, the extinguishment of other lights upon the vehicle with a consequent saving of current.

Having thus described the invention, what is claimed as new is:

1. A traffic signal including a signal casing, a pivoted semaphore blade normally housed within the casing, and a bell crank 115 pivoted within the casing and having one arm engaging with the blade at a point beyond the pivotal center of the blade, the other arm of said crank projecting from the casing and being accessible for manually 120 projecting the blade from the casing.

2. A traffic signal including a signal casing, a pivoted semaphore blade normally housed within the casing, a bell crank pivoted within the casing and having one 125 arm engaging with the blade, the other arm of said crank projecting from the casing and being operable for projecting the blade from the casing, and means carried by the casing to engage said last mentioned arm 130

of the crank for securing the crank holding the blade projected.

3. A traffic signal including a signal casing, a pivoted semaphore blade normally housed within the casing, a lever pivoted within the casing and engaged at one end with the blade, the opposite end of the lever being operable for projecting the blade from the casing, and resilient means carried by 10 the casing to clamp the latter end of said lever therebetween for securing the lever holding the blade projected.

4. In a traffic signal, the combination with a lamp casing, of a signal casing secured at one end to the lamp casing and suspended therefrom, a semaphore blade 15

normally housed within the signal casing and projectable therefrom, and means for projecting the blade, the lamp casing being adapted to receive a lamp for illuminating 20 the semaphore blade when projected.

5. In a traffic signal, the combination with a lamp casing and a pilot light therein, of a signal casing secured at one end to the lamp casing and suspended therefrom, a 25 semaphore blade normally housed within the signal casing and projectable therefrom, and means for projecting the blade, the pilot light being adapted to illuminate the semaphore blade when projected.

In testimony whereof I affix my signature. 30
CLARENCE M. BEADENKOPF. [L. S.]
